UNITED STATES PATENT OFFICE.

THOMAS A. HUTSELL, OF SPOKANE, WASHINGTON, ASSIGNOR OF ONE-FOURTH TO
GLENN S. HARDIN, ONE-FOURTH TO SAMUEL W. HOAG, AND ONE-FOURTH TO
ROY E. HUTSELL, ALL OF SPOKANE, WASHINGTON.

INTERNAL-COMBUSTION ENGINE.

1,269,937.

Specification of Letters Patent. Patented June 18, 1918.

Application filed August 31, 1916. Serial No. 117,912.

To all whom it may concern:

Be it known that I, THOMAS A. HUTSELL, a citizen of the United States, residing at Spokane, in the county of Spokane and State of Washington, have invented certain new and useful Improvements in Internal Combustion Engines, of which the following is a specification.

My invention relates to improvements in internal combustion engines, and more particularly to engines of this character of the rotary type.

The primary object of my invention is the provision of an engine or motor of very compact, comparatively simple and inexpensive construction but which possesses the smooth running qualities and almost continuous uninterrupted power and other advantages resulting from numerous explosive impulses per revolution such as provided by the conventional multiple cylinder type of internal combustion engine.

Broadly, my invention comprises a casing of novel form, a rotor or rotatable wheel mounted therein, a plurality of radially movable blades carried by the rotor, explosive charge intake and exhaust ports, ignition means, and an automatic self-circulating lubricating system.

The particular construction and mode of operation of my novel mechanism will be hereinafter described in detail, recourse being had to the attached drawings, in which—

Figure 1 is an elevation of the engine showing the casing and internal working parts in section.

Fig. 2 is a fragmentary transverse sectional view taken on line 2—2 of Fig. 1.

Fig. 3 is an enlarged detail view in section through the gas intake port.

Fig. 4 is a perspective view of the rotor or wheel member with the blades in the position shown in Fig. 1.

Fig. 5 is a sectional view through one of the rotor power blades.

Fig. 6 is a view showing one of the packing members carried by the rotor blades.

Referring more particularly to the drawings in which like reference characters are used to indicate like parts in the several views, the numeral 1 designates the engine casing as a whole which is preferably con-

structed in two parts and provided with the flanges 2 for bolting said parts together as 55 indicated at 3'. The casing further comprises an outer shell 3 and an inner shell 4 to provide a water cooling space 5.

Rotatably mounted within the casing and keyed at 6 upon the shaft 7 which is preferably journaled in double-course ball anti-friction bearing members 8 as shown in Fig. 2, is the rotor or rotatable wheel 9. This rotor is of solid construction and in the form of a true circle and has its peripheral 65 surface or rim portion 10 rounded from a true radius as shown in Figs. 2 and 4. The rotor is otherwise composed of the central hub portion 11, and one side bearing portion 12, these two latter portions and the 70 rim portion being cast integral. The remaining side portion 13 is preferably in the form of a removable circular plate which is screwed to the solid portion of the rotor as at 14. Both side portions 12 and 13 are 75 formed with the circumferential flange bearing faces 15. The solid portion of the rotor is further provided with the power blade receiving slots 16 in which are mounted six radially slidable power blades 17, each blade 80 having two spring recesses 18 in which are mounted the spiral springs 19 with their spring supporting pins 20 over which latter the springs are adapted to work, said pins having their fixed ends screwed into the 85 hub portion 11 of the rotor. The outstanding guide pins 21 which are integral with the narrow portions of the blades 17 extend through radial guide slots 22 of the rotor sides and are adapted to engage and ride in the irregular cam grooves 23 in the inner faces of the casing 1 as clearly indicated in Figs. 1 and 2. The spiral springs 19 of the power blades serve to tension the blades in an outward or circumferential direction 95 to maintain the bearing ends thereof in constant contact with the adjacent portions of the casing at all stages of rotation of the wheel or rotor. The cam grooves 23, it is obvious, are designed to guide the rotor power blades in proper relation to the inner circumferential portion or race-way of the casing, and are adapted to serve in harmony with the tensioning springs just described.

The chamber of the casing in which the

2
rotor is mounted and housed is of irregular curvilinear circumferential contour or outline, as shown in Fig. 1, the upper circumferential portion 24 and the lower circumferential portion 25, being drawn from the same center as the rotor and conforming with the rotor rim, while the end portions of the casing are designed to form and provide the compression and the combustion chambers 26 and 27, respectively. As is apparent, the entire inner circumferential portion of the casing adjacent to the traveling power blades is designed to form a race-way for the blades. Circumferential bearing shoulders 28 are provided to correspond with and engage the flange bearing faces 15 of the rotor sides 12 and 13 above described.

20 A gas or explosive charge intake port 29 is disposed to admit a proper mixture from the carburetor such as indicated at 30 through a manifold 31 to the compression chamber 26, while an exhaust port 32 is suitably disposed at the lower portion of the combustion chamber 27. A spark plug 33 to provide the necessary ignition is mounted in the casing at the upper portion of the chamber 27.

30 In order to provide a gas tight bearing surface between the rotor and the casing I have provided suitable packing strips 34 between the bearing faces 15 of the rotor and the bearing shoulders 28 of the casing; and it is also necessary to provide an adequate means for preventing the escape of gas past the extended portion of the rotor blades for the effective operation of the motor. To this end I have provided the extended portion of each blade with the groove or recess 35 to receive the forked spring packing member 36 which is formed, in contour, similar to the extended portion of the blades and is provided with sufficient outward spring in its pronged portions 37 to insure constant engagement with the contiguous or adjacent inner wall of the casing chamber or blade race-way. Each of these packing members 36 has the inwardly extending lugs 38 which engage with the groove or recess 35 of the blades so as to extend the curved portion of the packing member outwardly and into firm engagement or contact with the inner surface of the casing or blade raceway. The spring tension of the pronged portions 50 of the packing members, fulcruming on the lugs 38, is designed to provide a close packing fit at all points during rotation; but to insure engagement against the extreme outer diameter of the race-way a spring 39 has 60 either end fitted against the lugs 38 and serves to keep the packing member advanced and against the chamber wall. Still further packing means are provided for the blades consisting of the packing strips 40 which 65 are secured within the power blade receiv-

ing slots 16 and extend across the full width of the blades to prevent leakage past the blades to the interior recesses and passages of the rotor.

70 In order to properly oil or lubricate the mechanism, I provide a system which constitutes a very important feature of my invention and of which 41 is the feed pipe leading from any desired source of supply and connecting into the engine at 42 in the 75 side of the casing 1. A passage 43 carries the lubricant to an annular channel 44 in the rotor, as shown in Fig. 4. From this annular channel are passages 45 leading to each of the blade chambers or receiving 80 sockets or slots 16. Connecting each of these sockets are channels 46 leading from one socket to another so that all are in communication. It is obvious that the lubricant may be introduced into the motor from both or 85 only one side of the casing.

When the engine is running and the chambers or blade sockets are full of oil, the retraction of any one blade will force the oil within such chamber in either direction 90 through the communicating channels to the chambers where the blades are extended more or less, thus serving to keep a balance and to maintain an oil cushion against which the blades are retracted to prevent 95 clatter and undue stress by retraction. The blades will act much in the manner of pumps in expelling the oil from chamber to chamber, and also serve to maintain an equal and sufficient amount of lubrication 100 throughout the motor.

105 By reference to Fig. 5 it will be seen that the oil system is extended up into the spring recesses 18 in the power blades and from thence through channels or ducts 47, 48, and 49 to the under side of the blade packing members 36 where it will serve to fill the space between the blade slots and the packing members to further cushion the latter and provide a tight packing, while the surplus oil which passes the packing members 110 is sufficient to oil the race-way to overcome excessive friction.

115 The centrifugal action of the rotor will serve to throw the oil outward to provide a constant and adequate amount of lubricant for the blades, and also a surplus which will be thrown against the casing walls or race-way.

120 At the bottom of the casing at 50 is provided a sump or oil reservoir provided with a drain 51, for any surplus oil, which sump connects with the interior casing by means of numerous small openings 52 which act as exits from the interior of the casing to the 125 sump without interfering with the movement or travel of the blades over this portion of the race-way.

130 To provide a proper uninterrupted guidance in traveling over the intake and ex-

haust ports, the ports are not entirely cut open, but are provided with bridges 53 over which the ends of the power blades may pass freely without having to bridge a gap 5 in the race-way.

As stated, the ignition for the engine is provided by means of a spark plug suitably connected and mounted in the casing of the engine at the upper portion of the combustion chamber, as shown, and the explosion takes place when the blade just below the plug is in the position shown in Fig. 1 and while the gas is compressed within the space 54 of the combustion chamber. The gas enters through the intake port being drawn into the compression chamber by suction of the power blades, and is then forced into the portion 55 of the compression chamber from whence it will be squeezed through the constricted passage 56 and compressed fully within the temporary space 54 before a preceding blade and at the ignition point below the spark plug. The rotor and its casing are spaced approximately one-sixteenth of 25 an inch apart at the portion or passage 56 to allow for the gas passage during the process of compression.

Suitable stationary brackets 57 are designed to properly support the engine.

From the foregoing description of the elements of my motor and the explanation of its operation, it is apparent that I have provided a complete and practical internal combustion engine of simple, inexpensive, and 35 very compact construction which fulfils the objects or purposes of the invention in a thorough manner.

Manifestly, by proper timing of the ignition, six power impulses per revolution of 40 the rotor are obtained so that almost constant power will be transmitted to the rotor shaft, resulting in a very powerful and smooth running engine.

The intake and exhaust ports are at all 45 times open, and the construction obviates the necessity for complicated and expensive timed valves. The explosive charge or mixture is drawn into the compression chamber by suction due to the rotation of the power 50 blades, which blades also serve to properly

compress the same and to expel the burnt gases, as is clearly evident.

Having described my invention, I claim:—

1. In an internal combustion engine, the combination of a casing, a rotor rotatably mounted therein, radial power blade receiving slots in the rotor, radially movable power blades mounted in said slots, a lubricating and power blade cushioning means comprising an oil passage through the casing wall, oil ducts in said rotor sides adapted to communicate with and convey oil from said passage to said power blade receiving sockets, additional oil passages interconnecting said slots, oil channels from said sockets leading to and through the outer ends of said power blades, charge intake means and gas exhaust means communicating with the interior of said casing, and means for igniting said charge. 70

2. In an internal combustion engine, the combination of a casing, a rotor rotatably mounted therein, radial power blade receiving slots in the rotor, radially movable power blades mounted in said slots, a groove 75 in the extended end portion of each blade, a spring packing member mounted in each groove, a lubricating and power blade cushioning means comprising an oil passage through the casing wall, oil ducts in said 80 rotor sides adapted to communicate with and convey oil from said passage to said power blade receiving sockets, oil passages from said sockets to said grooves, charge intake and gas exhaust means communicating 85 with the interior of the casing, and ignition means for the charge.

3. In an internal combustion engine, the combination of a casing, a rotor rotatably mounted therein, radial power blade receiving slots in the rotor, radially movable power blades mounted in said slots, a groove 90 in the extended end portion of each blade, a spring packing member mounted in each groove, oil passages from said sockets to 95 said grooves, and intake, exhaust, and ignition means.

In testimony whereof I affix my signature.

THOMAS A. HUTSELL.
